UNITED STATES PATENT OFFICE.

JOSEPH REGENSTEIN, OF CHICAGO, ILLINOIS.

PROCESS FOR THE MANUFACTURE OF DOOR-PANELS AND THE LIKE.

1,259,286.

Specification of Letters Patent. Patented Mar. 12, 1918.

Application filed July 23, 1917. Serial No. 182,298.

To all whom it may concern:

Be it known that I, JOSEPH REGENSTEIN, a citizen of the United States, residing at Chicago, county of Cook, and State of Illinois, have invented certain new and useful Improvements in Processes for the Manufacture of Door-Panels and the like, of which the following is a specification.

The present invention has to do with certain improvements in process for the manufacture of door panels and the like which are used in the construction of automobile bodies and similar structures. For the purposes of convenience in describing and illustrating I will explain the features of the invention as applied to use in connection with the manufacture of door panels for automobile bodies, but I wish it understood that in so doing I do not intend to limit myself to this particular application of the invention. Nevertheless, as will presently appear, the features of the invention are very well adapted for this particular class of service.

In the manufacture of doors for automobile bodies it is customary to finish the inner faces of the doors by the use of the door panels which, while constituting a portion of the door and possessing the necessary physical strength, etc., should also present a neat and attractive appearance. Ordinarily the door panel is protected more or less from the weather but there are times when it is exposed to the action of rain and snow. Furthermore, during the cleaning of the interior of the car body the door panels are frequently flushed with water so that they must be so constructed as to resist not only the action of the elements but also the application of water in the ordinary cleaning process.

In the construction of certain makes of car bodies, some material other than leather is used, in order to bring the cost of manufacture within reasonable limits. Nevertheless there is a great demand for cars having a leather interior finish. It is therefore very desirable to build the door panels from material other than leather, while at the same time giving them the neat and attractive appearance possessed by a leather panel. For this purpose the use of paste board or the like backed up with heavy canvas or water proof cloth has come into extensive favor. Frequently this cloth itself is embossed besides being blackened or colored so as to give it the appearance of a leather finish. Difficulty has, however, been experienced in

applying the cloth to the card board or paste board backing in such a manner as to successfully resist the entrance of water between the cloth and the paste board. In fact a large portion of the initial cost of panels of this type has been occasioned by the necessity of making a thoroughly water tight connection between the cloth and the paste board backing. Not only this, but also it has been the experience that the very action of applying the cloth to the paste board backing has to a large extent injured or destroyed the embossed finish of the cloth so that the appearance of the completed product is thereby proportionally injured, and the desirability of this product proportionally lowered.

One of the objects of the present invention is to provide a method of application of the cloth surfacing or finish to the paste board or card board backing, such that the entrance of water and the like will be very successfully resisted and prevented while at the same time very materially lowering the cost of carrying on the process of manufacture. In this connection another object is to economize in the use of the raw materials, so conducting the process that the completed panels can be made from the use of a minimum amount of raw material.

Another object of the invention is to so relate or carry forward the various steps of the process that the completed product will present the best possible appearance and will most successfully present the appearance of embossed leather or the like which it is supposed to represent and imitate. Another object of the invention is to relate the various steps of the process to each other in such a manner that they will most successfully accomplish the foregoing objects, bearing in mind the particular application of the invention and its steps to use in the manufacture of door panels, for automobile bodies. Other objects and uses of the invention will appear from a detailed description of the same, which consists in the steps of process properly correlated and carried forward as hereinafter explained.

Before proceeding to a description of the drawings, I will first explain in brief outline the various steps of the process and the manner in which they are conducted so that the significance of the various figures of the drawings will be better understood when they are described.

In carrying forward the process of the

present invention, I first take a section of the backing material and apply to one face of the same the facing or covering of cloth or canvas. In order to economize in the cost of manufacture and in the use of materials, it is preferable to take a relatively large section of this backing material, such for example as a long strip of the same and having a width approximately equal to one of the dimensions of the completed panels. Furthermore, this backing material may be of any suitable composition, but preferably paste board or card board, the same being relatively cheap while being thoroughly applicable to the present use.

To one face of this strip of paste board or the like I glue or otherwise attach a strip of canvas or similar cloth fabric having a sufficiently close surface weave to give the desired appearance to the completed product. The attachment of the canvas or other cloth to the paste board is preferably in the form of a long continuous strip of whatever width may be found desirable but generally a width approximately equal to one of the dimensions of the completed panel. After the cloth fabric has dried the strip of material is to be painted or coated with a water-proofing material, and also when it is desired to give the same the appearance of leather or the like it should also be embossed. Assuming that both of these steps are to be performed, the strip should be coated with a coating of water-proofing material of the desired color generally black or in some cases brown. This water-proofing material serves not only to water proof the cloth fabric, but it serves also to fill in the pores and give the desired finish.

After the strip thus treated has dried, it may be embossed. This embossing consists in roughening or corrugating the material so that it will present more accurately the appearance of a strip of leather. In the past, the embossing has generally been formed on the cloth fabric before the same is attached or applied to the paste board backing. As a result of this procedure it is generally found that the completed product has lines or stripes on its face wherein the embossing has been rolled or pressed out by the tool used in applying the cloth to the paste board backing. Furthermore, it naturally follows that when this method of procedure is used, that the cloth does not adhere uniformly and effectively to portions of the paste board backing because the cloth is roughened by the embossing process, whereas, the paste board backing has a smooth, even surface.

In order to overcome this objection, in the present process I emboss the material after the cloth has been applied to the paste board, so that the roughening or corrugating attendant upon the embossing process

extends clear through the cloth and the backing. In this way not only is the appearance of the product greatly improved but also its strength and durability and permanency are markedly improved. Ordinarily this embossing will be done after the coating with the water-proofing or coloring material.

After the material has been embossed, the strip is cut up into blanks of the exact form and contour of the completed panels. It is to be observed that by so cutting the strip into blanks a raw edge is formed around the blank so that water or the elements might find their way between the cloth and the paste board by way of this raw edge. I have therefore, made provision for protecting this raw edge against any such possibility. Ordinarily such protection will be by way of a line of sewing or stitching extending clear around the blank and serving to solidly connect the edge of the cloth to the paste board backing. In other cases this protection may be afforded by way of a strip of cloth or water-proofing material extending clear around the door panel and folded or bent over the edge thereof and suitably attached thereto. The attachment by way of sewing around the edge of the blank is in many cases preferable on account of the low cost of manufacture and also the improvement in the form of the completed panel.

The panel as thus constructed is applied to the door frame in the usual manner, frequently by brads or tacks driven through the periphery of the panel and into the wooden backing of the door. Thereafter strips may be applied to the edge of the door.

In order that the features of invention and steps of process may be better understood, I will now refer to the drawings wherein—

Figure 1 shows a perspective view of a sheet of backing material;

Fig. 2 shows a perspective view of a sheet of backing material having applied to one of its faces a layer or sheet of cloth or fabric;

Fig. 3 shows on enlarged scale a cross section taken on the line 3—3 of Fig. 2 looking in the direction of the arrows, the coating of water-proofing material having been applied, and the strip of backing and cloth covering having been corrugated or embossed;

Fig. 4 shows a face view corresponding to Fig. 3;

Fig. 5 shows a view corresponding to Fig. 4, the blanks of several panels being indicated by the dotted and full lines;

Fig. 6 shows a face view of one of the panels cut out as indicated on Fig. 5, but having applied to its border or periphery a line of stitching or the like;

Fig. 7 shows a face view of the completed door having applied thereto the panel;

Fig. 8 shows on enlarged scale a fragmentary cross-section through a portion of a door having applied thereto the panel of the present invention;

Fig. 9 shows a fragmentary front face view of the border or periphery of the panel showing the line of stitching;

10 Fig. 10 shows a fragmentary back face view corresponding to Fig. 9;

Fig. 11, shows a fragmentary edge view corresponding to Figs. 9 and 10;

15 Fig. 12 shows a fragmentary face view of an edge of a panel having applied thereto a modified form of binder; and

Fig. 13 shows a cross section corresponding to Fig. 12.

Referring now to the several figures, I 20 first take a section of backing material such as paste board or the like and apply to one of its faces a layer of canvas or other suitable fabric. This may be the long continuous strip of paste board (14) shown in Fig. 25 1, having applied to one of its faces a long continuous strip of canvas or other fabric (15) shown in Fig. 2. The canvas or cloth fabric so applied is attached to the paste board or other backing, by paste or glue, 30 and this application is preferably made when both the paste board backing and the canvas or cloth strip are flat so that a very even and uniform attachment will be secured.

35 The canvas or other fabric is then treated with a coating of water-proofing material, preferably of a color which will give the desired finish according to the imitation leather finish desired. This is the coating (16) shown in Fig. 3. Either before or after the application of the water-proofing material, the backing and the cloth or canvas covering are corrugated or embossed so as to roughen the strip and make it more 45 perfectly resemble the leather which it is supposed to imitate. This corrugating or embossing is clearly shown in Fig. 3. It is to be observed that by performing this corrugating or embossing step on the strip after 50 the cloth or canvas has been applied to the backing, the corrugating or embossing roughening will extend clear through the back as well as the cloth. Furthermore, inasmuch as the pasting or gluing operation

55 has already been completed when the parts are in smooth or uncorrugated condition it follows that a very perfect connection between them is possible. Furthermore when this process is used, there is no danger of 60 eradicating any of the embossing finish during the process of applying the cloth to the paste board backing.

With the large sheet or strip finished to the point so far explained it is to be cut up 65 into blanks of the desired size and form

according to the door panels to be manufactured. The dotted lines 17 and 18 in Fig. 5 indicate the position of two of the blanks which are to be cut out and the full line 19, in said figure indicates one of the 70 blanks which is being cut out or has been already cut out.

After each blank has been cut away from the large sheet or strip its edge portion will be raw or unprotected. The card board or 75 paste board backing as well as the cloth will have their edges exposed so that water and the like would very easily find their way into this raw edge. I therefore provide a protection for the raw edge in the form of 80 a line of stitching 20, extending all around the periphery of the blank as shown in Fig. 6, or a strip of binding material as shown in Figs. 12 and 13, or any other suitable protection. The stitching is in many ways very 85 desirable for this purpose because it not only actually binds or holds the cloth and paste board together, but when it is of the form shown in Figs. 9, 10 and 11, it also actually protects the edge of the blank because it extends across said edge as shown in Fig. 11. Therefore the next step in the process consists in the application of a suitable binding or protecting material to the 90 edge or periphery of the blank.

95 The door panel is then ready for application to the door. The door illustrated in Fig. 8 comprises a metal or other pan shaped receptacle (21) having around its periphery a block of wood or the like (22) which 100 serves to space the door panel (23) from the bottom of the pan, and also serves as a medium to which the panel may be secured by the use of nails or brads (24). These same nails or brads may be used for attaching a finishing strip (25), which comprises a folded strip (26) and a cord or bead (27).

105 In the modified panel shown in Figs. 12 and 13, a binding strip (28) is folded over the edge of the panel, and is held in place 110 by a line of stitching 29.

While I have herein shown and described only certain embodiments of the features of my invention, and a certain sequence of steps of process, still it will be understood 115 that I do not limit myself to the same, except as I may do so in the claims.

I claim:

1. The process for the manufacture of door panels or the like which consists in first 120 applying to a relatively large smooth sheet of backing material comprising paste board or the like, a sheet of cloth fabric of desired texture, by pasting or gluing, thereafter painting said fabric with a water-proofing 125 and coloring material, thereafter embossing the sheet thus prepared by means of corrugations extending clear through the backing material and the fabric, thereafter cutting the said sheet so prepared into blanks 130

of the desired size and shape, and thereafter forming a border of stitching around the periphery of the blank so cut, said stitching extending clear through the material of the 5 backing and the fabric for the purpose of firmly joining together the fabric and the backing around the periphery of the blank to protect the same against the entrance of water, substantially as and for the purpose 10 set forth.

2. The process for the manufacture of door panels and the like which consists in first gluing or pasting a sheet of textile fabric of desired weave to the face of a 15 smooth sheet of backing material of paste board or the like, thereafter embossing the sheet so prepared by means of corrugations extending clear through the backing material and the textile fabric, thereafter cutting 20 the sheet so prepared into blanks of desired size and shape, and thereafter protecting the edges of said blanks against the entrance of water between the textile fabric and the backing material substantially 25 as and for the purpose set forth.

3. The process for the manufacture of door panels and the like which consists in first pasting or gluing a sheet of textile fabric of desired weave on to one face of a 30 smooth sheet of backing material, thereafter cutting the sheet so prepared into blanks of the desired size and shape, and thereafter

protecting the edges of said blanks by means of stitching extending around the peripheries of blanks and through the sheets of 35 textile fabric and backing material for the purpose of preventing the entrance of water substantially as and for the purpose set forth.

4. The process for the manufacture of water-proof door panels and the like having the appearance of leather, which consists in first applying to a relatively large smooth sheet of paste board or the like a sheet of cloth fabric or the like of desired texture by 40 pasting or gluing, thereafter painting said fabric with water-proofing and coloring material to give the same the appearance of leather finish and to protect the same against water, thereafter embossing the sheet thus 45 prepared by means of corrugations extending clear through the backing material and the fabric, thereafter cutting the said sheet so prepared into blanks of the desired size and shape, and thereafter forming a border 50 of stitching around the periphery of the blanks so cut, said stitching extending clear through and also over the edge of the backing and fabric for the purpose of firmly 55 joining together these parts to protect the same against the entrance of water, substantially as and for the purpose set forth.

JOSEPH REGENSTEIN.
